(57) **CLAIM**

The ornamental design for a shower seat, as shown and described.

DESCRIPTION

FIG. 1 is a top, front and side perspective view of a shower seat showing our new design;

FIG. 2 is a front elevational view thereof;

FIG. 3 is a side elevational view thereof from the left of FIG. 2;

FIG. 4 is a side elevational view thereof from the right of FIG. 2;

FIG. 5 is a rear elevational view thereof; and,

FIG. 6 is a top plan view thereof.

The appearance of the underside forms no part of the claimed design.
